UNITED STATES PATENT OFFICE.

WILLIAM J. CRUMPTON, OF EVANSTON, ILLINOIS, ASSIGNOR, BY MESNE ASSIGNMENTS, TO WILLIAM R. HEATH, OF BUFFALO, NEW YORK.

AUTOMATIC ACCOUNTING SYSTEM.

1,084,612.

Specification of Letters Patent.

Patented Jan. 20, 1914

Application filed March 6, 1909. Serial No. 481,732.

To all whom it may concern:

Be it known that I, WILLIAM J. CRUMPTON, a citizen of the United States, residing at Evanston, in the county of Cook and State of Illinois, have invented a certain new and useful Improvement in Automatic Accounting Systems, of which the following is a full, clear, concise, and exact description, reference being had to the accompanying drawings, forming a part of this specification.

My invention relates to an automatic accounting system, and has for its object the provision of a novel form of register actuating arrangement. In systems of this kind the registers heretofore devised—that is, the workmen's registers for taking account of the workman's time or wages, or both—have been actuated either by electromagnetic means or by means solely mechanical. In the first instance, the electroinagnetic mechanisms for actuating the registers are operated periodically at predetermined intervals. In other words, these mechanisms are so connected in circuit that they receive electrical impulses at a frequency depending upon the rate of actuation of the particular register. Registers provided with mechanisms of this kind are therefore actuated periodically, the rate of actuation varying in accordance with the rate of wages which the register is intended to represent. In other arrangements the use of electricity has been entirely dispensed with and the registers are actuated by means solely mechanical,—as, for instance, by connecting the registers with a time-controlled power shaft. However, in these mechanical arrangements the registers are driven continuously during the time in which they are operatively connected with the power shaft. Now, I have devised an arrangement whereby the registers are actuated periodically by means solely mechanical, the rate of actuation of any particular register depending upon the frequency of the mechanical impulses to which the register actuating mechanism is subjected by the time-controlled driving device. In this way I obviate the objection of running a register continuously during the time in which it is connected in,

and by dispensing with all electrical appurtenances such as electromagnets, switches, commutators, etc., I render the operation of the actuating device certain and positive.

Broadly speaking, one feature of my invention consists in providing a common actuating device for a series of registers, so arranged that at predetermined intervals an operative mechanical connection will be temporarily or momentarily established between the common driving device and any one or more of the registers, whereby the latter will receive an actuation every time such temporary mechanical connection is established. Furthermore, the arrangement is such that the workmen's registers are never actuated more than one at a time. In other words, these registers are actuated in succession. I have also shown a series of job-registers so arranged with relation to a series of wage-registers that unless a workman's plug is in "in" or operative position, the corresponding wage-register will be disconnected from its associated actuating mechanism. When the workman, however, moves his plug from "out" to "in" position, the corresponding wage-register will be connected with its actuating mechanism, while at the same time operative connection is established between this actuating mechanism and the workman's job-register which has been connected in service. Furthermore, a totalizer may be arranged for indicating the total of the actuations of the connected job-registers.

In order that my invention may be understood, I will now take up a detailed description of the same, reference being had to the accompanying drawings, in which—

Figure 1 represents a front view of an arrangement of wage and job-registers adapted to be actuated by my novel form of mechanism, a portion of the front cover being broken away to disclose part of the interior mechanism; Fig. 2 is an end view taken on line 2, 2 of Fig. 1, looking in the direction indicated by the arrows; Fig. 3 is a front view showing the driving belt detached and indicating in dotted lines a series of actuating mechanisms to show the way in which the rates of actuation of the

registers may be varied; Fig. 4 is an end view on line 4, 4 of Fig. 1, only the upper portion of the casing being broken away; Fig. 5 is a fragmentary detail view on line 5 of Fig. 1, showing how the motion of the register actuating mechanism is communicated to the shaft, which transmits the motion to the connected job-register; Fig. 6 is a fragmentary detail view on line 6 of Fig. 10 1 of a simple train of gears, showing how the motion of each job driving member is communicated to the job-registers; Fig. 7 is a fragmentary detail view, partly in cross-section, showing the position of one of the 15 transmitting shafts when the workman's plug is in its "out", or inoperative, position, whereby the corresponding actuating mechanism is thrown out of gear with its associated register, as will be more fully explained.

Like numerals refer to corresponding parts throughout the several views.

In the end walls 1 and 2 is journaled a series of shafts 3, 4, 5 and 6. Although but 25 four of these shafts have been shown in the drawings, yet it is evident that any number might be used, depending upon the size of the mechanism. I have endeavored to indicate this by showing the lower half of the 30 casing in Figs. 1, 2, 3 and 4 broken away at a. Upon the left end of each one of these shafts is mounted a register-actuating mechanism, which comprises a sleeve 7 loosely mounted upon the shaft and provided at its 35 right end with a driving gear 8 rigidly secured thereto so as to rotate therewith. At some intermediate point between its ends this sleeve has firmly mounted thereon an actuating pinion or toothed-wheel 9. Beside the driving gear 8 on the sleeve 7 is secured the ratchet wheel 10, as shown in Fig. 5. A housing 11 is firmly fixed upon the shaft 3 in proximity to the right end of the sleeve and is provided with a pivoted 40 pawl 12, as shown in Fig. 5. This pawl is normally held by a spring 13 in engagement with the teeth of the ratchet wheel 10. The result of this arrangement is that if the actuating mechanism be rotated in the direction indicated by the arrow in Fig. 5, the 45 rotation will be communicated to the transmitting shaft 3 through the medium of the ratchet wheel 10, pawl 12 and housing 11. Every one of the registers 14, 15, 16 and 17 50 has associated therewith such an actuating mechanism as that just described. This series of registers, which in the particular example illustrated might be considered to be wage-registers, is mounted upon the partition 18. This partition has an opening 19 beneath every one of the sleeves 7, in order 55 to permit certain of the parts of the associated actuating mechanism to extend beyond the partition, as shown in Fig. 2. Refer-

ring to the uppermost register 14, it will be seen that the same is provided with a gear 20, which is in mesh with the gear 8 of the actuating mechanism. In this way actuation of the latter is transmitted to the associated register 14 through the medium of the gears 70 8 and 20. For the sake of clearness I have in Fig. 1 shown only one of the registers, viz., that numbered 14 and its associated actuating mechanism. It is to be understood, of course, that every one of the other wage-registers is similarly arranged with respect to its actuating mechanism.

Let us now take up the description of the device which periodically actuates the registers. To the partition 21 is secured a bearing indicated in dotted lines at 22 in Fig. 1. In this bearing is journaled one end of the shaft 23, which has secured thereto the drum or roller 24. At the opposite end of the casing is journaled the drum or roller 25, and upon this pair of rollers is mounted an endless belt or band 26, preferably in the form of a thin metal such as steel. In order to prevent slipping of the belt on its rollers, I provide the upper roller 23 with a series of 85 lugs 27, which fit into the properly arranged holes 28 in the belt, whereby movement of the belt is insured strictly in accordance with the movement of the roller 24. The belt 26, as may be seen from Figs. 2 and 3, is provided with a series of transverse teeth 29, 30, 31, 32, etc. The front portion of the belt moves over the partition 33 to prevent the belt from being bent inwardly during its 90 operation. It will be noticed that the teeth 100 of the actuating wheels 9 on the register operating mechanisms extend into the path of travel of the teeth on the belt. This is clearly shown in Fig. 2. Assuming the shaft 23 to be uniformly driven as by a clock or 105 by some clock-governed motor, it will be seen that whenever one of the teeth on the belt comes into engagement with the projecting tooth of one of the actuating wheels 9, the latter will be given an actuation, the 110 amount of rotation being the distance of one tooth on the actuating wheel. The movement of the actuating wheel 9, of course, is transmitted to the gear 8 and from there to the associated register through the driving 115 gear 20. At the same time this operation of the register-actuating mechanism is communicated to the associated transmitting shaft through the medium of the ratchet wheel 10 and the housing 11, as previously 120 described. For the present we may omit further reference to this actuation of the transmitting shaft by the associated register-actuating mechanism. This will be taken up later in detail.

Referring to Fig. 2, it will be noticed that the arrangement of the teeth 29, 30, 31, 32, etc., is such with respect to the actuating

wheels 9 of the register-operating mechanisms that only one mechanism is actuated at a time and that the mechanisms are actuated successively. Thus, for instance, tooth 5 31 on the belt is in position to engage the actuating wheel of the mechanism associated with register 16. Tooth 32 has already passed the actuating wheel of the mechanism associated with register 17. The tooth 10 30 will be seen to be not as far away from the projecting tooth of the actuating wheel of the second mechanism, as is tooth 29 away from the projecting tooth of the actuating wheel of the first operating mechanism,— 15 that is to say, the mechanism belonging to register 14. In this way I secure the successive actuation of the registers periodically. It will be evident that the rate of actuation of any particular register depends upon the 20 frequency of the actuations of the wheels 9 by the teeth on the belt. For instance, the rate of actuation of a register whose mechanism was actuated by every one of the teeth on the belt would be twice that of a register 25 whose mechanism was actuated only by every other tooth on the belt. Therefore, by so arranging the teeth on the belt with respect to the actuating wheels of the register-operating mechanisms that a different number 30 of teeth shall actuate the various mechanisms during a certain interval of time, I am enabled to readily control the rate of actuation of every particular register. The simplest manner in which this scheme may 35 be carried out is by varying the length of the teeth.

Calling attention to Fig. 3, it will be seen that tooth 29 extends practically across the entire width of the belt at that point. 40 Tooth 30 does not extend to the extreme right end as does tooth 29. Tooth 31 will be seen to be even shorter than tooth 30, while tooth 32 extends but a little way across the belt. Now, by varying the positions 45 of the actuating wheels 9 on the various register-operating mechanisms, it will at once be apparent how the rate of actuation of any particular mechanism may be varied. To show how this variation takes place, I have indicated in dotted lines in 50 Fig. 3 several actuating mechanisms more or less diagrammatically showing the actuating wheel 9 in each instance in a different position transversely of the belt. For instance, the actuating mechanism 34 has its actuating wheel 34' upon the extreme right, so as to be engaged only by teeth such as 29, which extend across the entire width of the belt. Actuating mechanism 35 has 55 its actuating wheel 35' somewhat more to the left, so as to be engaged not only by the teeth 29 but also by teeth 30, which do not extend across the entire width of the belt. So that, while actuating wheel 35' would be

engaged by the teeth 29 and 30, the actuating wheel 34' will not be operated by the teeth 30. Actuating mechanism 36 has its actuating wheel 36' in position such that it will be engaged by the teeth 29, 30 and 31, but will not be engaged by the teeth 32. 65 Actuating mechanism 37 has its actuating wheel 37' so arranged that it will be engaged by all of the teeth 29, 30, 31 and 32. Whenever, therefore, it is desired to vary the rate 70 of actuation of any particular register, it is only necessary to vary the position of the actuating wheel 9 of the associated operating mechanism. Of course this might be done by making the wheel 9 of each mechanism adjustable on the sleeve 7, but it would 80 be probably more convenient to have on hand a supply of these mechanisms in which the actuating wheel 9 is arranged in various positions to correspond with various rates, so that it would only be necessary to substitute one mechanism for another to effect 85 the desired change of rate. The readings of the registers are observed through the sight openings 38 in the front wall 39.

In order to prevent actuation of the 90 wheels 9 other than by the teeth on the belt, I have devised a sort of locking arrangement whereby accidental movement of these wheels is absolutely prevented. This locking arrangement simply consists in providing a disk 40 on the sleeve 7 of such configuration that in any position of the actuating wheel 9 this disk will present a flat surface to the moving belt 26 and will impinge upon the belt, should for some cause 100 or other the wheel 9 be accidentally moved. In the drawings I have shown these locking disks in the form of hexagons, but the particular number of sides will depend upon the particular number of teeth on the actuating wheel 9. To permit rotation of these locking disks when the actuating wheels 9 are moved by the teeth on the belt, I provide the latter with cut-away portions 41, on the left side of the belt opposite each tooth, as 105 is clearly shown in Fig. 3. Furthermore, the partition 38 is provided with depressions 42 opposite each locking disk, as shown in Fig. 2. It will be seen that in this way the edge or corners of the locking disks will 110 find an unobstructed path of travel through the cut-away portions 41 and the depression 42, whenever an actuating wheel 9 is operated by one of the teeth on the driving belt.

I now direct attention to the job-registers which I have shown associated with the wage-registers so as to be operated by the actuating mechanisms of the wage-registers. In the partition 21 and the end wall 2 is 115 journaled a shaft 43, as shown in Figs. 1 and 4. To the longitudinal partition or support 44 is secured a series of job-registers

45, 46, 47 and 48. Each one of these registers is provided with an actuating gear 49. This gear engages the idler 50 suitably supported, and this idler in turn meshes with 5 the teeth of the gear-wheel 51, loosely mounted on the shaft 43 and fixed upon the associated sprocket wheel by means of the hub or sleeve 43', as shown in Figs. 1 and 6. In this way rotation is communicated 10 to the job-registers. The sprocket wheel 52, associated with each of the registers 45, 46 and 47, is loosely mounted upon the shaft 43. On this sprocket wheel works a chain 53, which is supported in the lower end of the 15 casing on a similar sprocket wheel, so as to form a readily revoluble endless chain. The sprocket chain 53 is merely one form of motion-transmitting device that may be used in this connection and any other suitable form may be employed. The sprocket 20 wheels 52 are each provided with a pivoted pawl 53', which is normally held by the spring 54 in engagement with the teeth of the ratchet wheel 55 fixed upon the shaft 25 43. From this it will be seen that if the sprocket chain 53 be moved in the direction indicated by the arrow in Fig. 4, the wheel 52 will, through the medium of the pawl 53', carry with it the ratchet wheel 55, thereby 30 actuating the shaft 43 by a corresponding amount. However, forward rotation of the shaft 43 will have no effect upon the sprocket wheels 52 or the chain 53, for the reason that the teeth of the ratchet wheel 55 will 35 ride under the pawl 53'.
 The way in which connection is made between the sprocket wheel belonging to any particular job-register and the workman's wage-register is as follows: We have seen 40 above that with each of the register-operating mechanisms is associated a transmitting shaft 3, 4, 5 or 6. We have also seen how the actuation of any register-operating mechanism is communicated to the associated transmitting shaft through the medium of the ratchet wheel 10, pawl 12 and housing 11. For the sake of clearness let us consider the transmitting shaft 3, which is associated with the actuation mechanism 45 belonging to the wage-register 14. Keyed upon this shaft is a clutch member shown in the form of a toothed wheel 56. This wheel may therefore be moved longitudinally on the shaft, but it will rotate there- 50 with. On either side of this toothed wheel are the extensions 57 and 58 of the yoke 59, as most clearly indicated in Fig. 7. To this yoke is secured the extension 60. In Fig. 4 I have shown this extension as being 55 screw-threaded into the upper portion of the yoke 59. Slidably mounted on this extension is a finger portion 61 normally held against the front wall of the casing by means of the spring 62. The extension 60, 60 finger portion 61 and yoke 59 might be

termed the workman's plug, since that is what they in effect constitute, so that the workman's plug controls the position of the wheel 56 on its transmitting shaft. The extension 60 moves in a slot 62 in the front 70 wall of the casing, as shown in Fig. 1, there being as many of these slots as there are workmen's plugs. The "out" or inoperative position of a workman's plug is the position in which the plugs are shown 75 in Fig. 1. In order to insure the proper alinement of the plugs with respect to other parts, I provide a circular depression or recess 63 at the points where the plug is to be placed. For instance, in Fig. 1, these 80 depressions are in alinement with the sprocket chains of the job-registers, so as to insure the alinement of the plug with the particular sprocket chain with which it is desired to connect any particular register-operating mechanism. The lower conical portion 64 of the finger piece 61 fits into the depression 63, whereby accidental displacement of the plug is prevented. 85

It will be observed in Fig. 1 that the gears 90 8 and 20 are in mesh, whereby the register 14 is operatively connected with its associated actuating mechanism. Now, when the plug which controls the wheel 56 on that shaft is in its "out," or inoperative, position, 95 as shown in Fig. 7, the yoke 59 will have moved the shaft 3 a little to the right against the action of the spring 65. This shifting of the shaft to the right is indicated in Fig. 7 by the shaft 3 being shown 100 as projecting beyond the partition 2 to a greater extent than it is shown projecting in Fig. 1. When the shaft 3 is thus shifted to the right the sleeve 7 and the housing 11, together with all their associated wheels, are 105 shifted with the shaft, whereby the gear 8 is thrown out of mesh with the driving gear 20 of the register 14. So that when a workman's plug is in the "out," or inoperative, position his wage-register is disconnected 110 from its associated actuating mechanism. In order, therefore, to connect a workman's wage-register in, it is necessary that his plug be moved from the "out" position into alinement with one of the sprocket chains 115 53. When this is done the wheel 56 will be placed in mesh with the sprocket wheel of the particular job-register which it is desired to connect into service. With the parts in this position it is clear that the actuation 120 of the register-operating mechanism belonging to the workman's register will be transmitted to, let us say, shaft 3 and from there by means of the wheel 56 to the sprocket chain 53 belonging to one of the job-registers. The movement of the sprocket chain is communicated to the associated job-register in the manner already above described. The 125 gearing arrangement is, of course, such that the job-register is actuated the same amount 130

- as the wage-register with which it is connected. The actuations of any wage-register and its connected job-register take place concurrently, although the actuations of the wage-registers take place in succession, as we have seen above. It will also be clear that the rate of actuation of any job-register will always be the same as the rate of actuation of the connected wage-register.
10. It will be observed that the register 48 in Fig. 1 has not associated therewith a sprocket chain like the other registers. The reason is that the register 48 is a summation-register and is connected with the shaft 43 by means of a train of gears. So that all of the actuations of the shaft 43 are transmitted into this totalizing register 48, whereby this register will indicate the correct total of the actuations of the job-registers.
15. Because of the pawl-and-ratchet connection between the register-actuating mechanisms and their associated transmitting shafts, it is impossible for the actuations of a sprocket chain to be transmitted back through one of the transmitting shafts to some other wage-register. If, for instance, there were two plugs in the openings A and B in Fig. 1, the actuations of the corresponding wage-registers would, as before explained, take place successively. Now, if the actuating mechanism of one of the corresponding wage-registers be operated by a tooth on the belt, the motion will be communicated to the associated transmitting shaft 4 and from there through the wheel 56 to the sprocket chain 53. The movement of the sprocket chain will actuate the job-register 45 as above explained. At the same time the movement of the sprocket chain will rotate the wheel 56 on the shaft 5. However, this rotation of the shaft 5 will have no effect on the corresponding register-operating mechanism, for the reason that the pawl 12 in the housing 11 will ride over the teeth of the ratchet wheel 10.
20. It will be seen that the above-described mechanism automatically takes account of a workman's time and wages by compelling concurrent actuation of any wage-register and its connected job-register by a step-by-step movement, and that the workman moves his plug to make connection with some job-register in order to actuate his wage-register. Now, it may happen that a workman, through no fault of his own, will not be assigned to any particular job, and yet he ought not to be deprived of his wages for the time during which he is thus idle. In that case, the register 47 will act as the 25 "waste time" register. That is to say, a workman, when not assigned to any job, will move his plug to the opening next to the one which holds the plug in its "out" position, in order to connect the register 47 into service. In this way, all waste time is
- taken account of by the register 47, so that the difference between the amount indicated by the summation-register 48 and the amount indicated by the "waste time" register 47, will represent the effective jobs, or the sum of the indications of the effective job-registers.
25. Although I have herein shown and described certain specific constructions and arrangements, yet I would have it understood that such description and illustration are by way of example only and for the purpose of conveying a clear understanding of my invention. It is evident that various changes and modifications may be resorted to as coming within the scope of my invention. Furthermore, it is obvious that certain features may be used without other features, as clearly indicated in the appended claims.
- Having now described my invention, what I desire to secure by Letters Patent is:
1. The combination of a register, time-controlled driving mechanism normally disconnected from said register, and means for establishing mechanical connection between said mechanism and said register at regularly recurring intervals for actuating the register by a step-by-step movement.
2. The combination of a register, time-controlled driving mechanism normally disconnected from said register, means for establishing mechanical connection between said mechanism and said register at regularly recurring intervals for actuating the register by a step-by-step movement, and means for varying the rate of actuation of said register without change in the rate of operation of the time-controlled driving mechanism.
3. In combination, a plurality of registers, a common time-controlled driving mechanism associated therewith, and means for periodically and successively establishing an operative mechanical connection between each of said registers, or any number thereof, and said mechanism, whereby the registers are actuated in succession by a step-by-step movement.
4. In combination, a plurality of registers, a common driving mechanism associated therewith, means for periodically and successively establishing an operative mechanical connection between each of said registers, or any number thereof, and said mechanism, whereby the registers are actuated in succession by a step-by-step movement, and means for automatically totalizing the actuations of said registers.
5. In combination, a plurality of registers, a common driving mechanism associated therewith, means for periodically and successively establishing an operative mechanical connection between each of said registers, or any number thereof, and said mechanism, whereby the registers are actuated in succession by a step-by-step movement.

- sion by a step-by-step movement, and means for varying the rate of actuation of any of said registers.
6. In combination, a plurality of registers, 5 a common driving mechanism associated therewith, means for periodically and successively establishing an operative mechanical connection between each of said registers, or any number thereof, and said mechanism, 10 whereby the registers are actuated in succession by a step-by-step movement, means for varying the rate of actuation of any one of said registers, and means for automatically totalizing the actuations of said registers.
- 15 7. The combination with a plurality of registers, of time-controlled means solely mechanical for periodically actuating said registers or any number thereof in succession by a step-by-step movement.
- 20 8. The combination with a plurality of registers, of time-controlled means solely mechanical for periodically actuating said registers or any number thereof in succession by a step-by-step movement, and means for 25 automatically totalizing the actuations of said registers.
9. The combination with a plurality of registers, of means solely mechanical for periodically actuating said registers or any number thereof in succession by a step-by-step movement, and means for varying the rate of actuation of any one of said registers.
- 30 10. In combination, one or more wage registers, a job register, an actuating means, 35 devices solely mechanical for operating such job register concurrently with the wage registers by a step-by-step movement from said actuating means, devices for connecting the registers and disconnecting them from the 40 actuating means, and mechanism for totalizing the operation of the wage registers as desired in the job register.
- 45 11. In combination, a wage register, a plurality of job-registers, means for selectively establishing operative connection between said wage-register and any one of said job-registers, and means solely mechanical for periodically actuating said wage-register and the connected job-register concurrently 50 by a step-by-step movement.
- 55 12. In combination, a wage-register, a plurality of job-registers, means for selectively establishing operative connection between said wage-register and any one of said job-registers, means solely mechanical for periodically actuating said wage-register and the connected job-register concurrently 60 by a step-by-step movement, and means for varying the rate of actuation of said wage-register.
- 65 13. In combination, a wage-register, a plurality of job-registers, means for selectively establishing operative connection between said wage-register and any one of 65 said job-registers, means solely mechanical
- for periodically actuating said wage-register and the connected job-register concurrently by a step-by-step movement, and a summation-register for automatically totalizing the actuations of the connected job-registers. 70
14. In combination, a plurality of individual wage-registers, a job-register associated therewith, means solely mechanical for periodically actuating said wage-registers or any number thereof in succession by a step-by-step movement at predetermined rates, and means for selectively establishing operative connection between said job-register and any one of said wage-registers, 75 whereby said job-register will be actuated concurrently with the connected wage-register. 80
15. In combination, a plurality of individual wage-registers, a job-register associated therewith, means solely mechanical for periodically actuating said wage-registers or any number thereof in succession by a step-by-step movement at predetermined rates, means for selectively establishing operative connection between said job-register and any one of said wage-registers, 85 whereby said job-register will be actuated concurrently with the connected wage-register, and means for varying the rate of actuation of any one or more of said wage-registers. 90
16. In combination, a plurality of individual wage-registers, a plurality of individual job-registers associated therewith, means solely mechanical for periodically actuating said wage-registers or any number thereof in succession by a step-by-step movement at predetermined rates, and means for selectively establishing operative connection between any wage-register and any job-register to cause concurrent actuation of 100 said connected registers. 105
17. In combination, a plurality of individual wage-registers, a plurality of individual job-registers associated therewith, means solely mechanical for periodically actuating said wage-registers or any number thereof in succession by a step-by-step movement at predetermined rates, means for selectively establishing operative connection between any wage-register and any job-register to cause concurrent actuation of 110 said connected registers, and a summation register for automatically totalizing the 115 actuations of the connected job-registers. 120
18. In combination, a register, actuating means associated therewith, and a time-controlled driving mechanism adapted to periodically engage said register-actuating means for operating the same, whereby the register is actuated by a step-by-step movement. 125
19. In combination, a plurality of registers, actuating means associated with each 130

- register, and a time-controlled driving mechanism common to all registers and adapted to periodically and successively engage said register-actuating means for operating the same, whereby the registers are actuated in succession by a step-by-step movement.
20. In combination, a plurality of registers, actuating means associated with each register, a time-controlled driving mechanism common to all registers and adapted to periodically and successively engage said register-actuating means for operating the same, whereby the registers are actuated in succession by a step-by-step movement, and means for automatically totalizing the actuations of said registers.
21. The combination of a register, an actuating mechanism associated therewith, and a time-controlled driving belt provided with teeth which periodically engage said mechanism to cause movement thereof, whereby the register is actuated by a step-by-step movement.
25. 22. The combination of a plurality of registers, an actuating mechanism associated with each register, and a time-controlled driving belt common to all registers and provided with teeth which periodically and successively engage the register-actuating mechanisms to cause movement thereof, whereby the registers are actuated in succession by a step-by-step movement.
35. 23. The combination of a plurality of registers, an actuating mechanism associated with each register, and a time-controlled driving belt common to all registers and provided with teeth which periodically and successively engage the register-actuating mechanisms to cause movement thereof, whereby the registers are actuated in succession by a step-by-step movement, said teeth varying in length to produce different rates of actuation of said registers.
45. 24. The combination of a plurality of registers, an actuating mechanism associated with each register, a time-controlled driving belt common to all registers and provided with teeth which periodically and successively engage the register-actuating mechanisms to cause movement thereof, whereby the registers are actuated in succession by a step-by-step movement, and a summation-register for automatically totalizing the actuations of said registers.
55. 25. The combination of a plurality of registers, an actuating mechanism associated with each register, and a time-controlled driving belt common to all registers and provided with teeth which periodically and successively engage the register-actuating mechanisms to cause movement thereof, whereby the registers are actuated in succession by a step-by-step movement, said teeth varying in length to produce different rates of actuation of said registers.
5. of actuation of said register and a summation-register for automatically totalizing the actuations of said registers.
26. The combination of a driving belt provided with a series of teeth, a register, and an actuating mechanism adapted to be geared thereto and having a toothed-wheel projecting into the path of travel of the teeth on the belt, whereby said teeth are periodically brought into engagement with said toothed-wheel to rotate the same and thereby actuate the register by a step-by-step movement.
27. The combination of a driving belt provided with a series of transverse teeth, a plurality of registers, and an actuating mechanism for each register, said mechanism including a toothed wheel projecting into the path of travel of the teeth on the belt, whereby said teeth are periodically and successively brought into engagement with the toothed wheels to rotate the same and thereby actuate the registers in succession by a step-by-step movement.
28. The combination of a driving belt provided with a series of transverse teeth, a plurality of registers, and an actuating mechanism for each register, said mechanism including a toothed wheel projecting into the path of travel of the teeth on the belt, whereby said teeth are periodically and successively brought into engagement with the toothed wheels to rotate the same and thereby actuate the registers in succession by a step-by-step movement, said teeth varying in length and said toothed wheels varying in position to produce different rates of actuation of said registers.
29. The combination of a driving belt provided with a series of transverse teeth, a plurality of registers, an actuating mechanism for each register, said mechanism including a toothed wheel projecting into the path of travel of the teeth on the belt, whereby said teeth are periodically and successively brought into engagement with the toothed wheels to rotate the same and thereby actuate the registers in succession by a step-by-step movement, and a summation-register for automatically totalizing the actuations of said registers.
30. The combination of a driving belt provided with a series of transverse teeth, a plurality of registers, an actuating mechanism for each register, said mechanism including a toothed wheel projecting into the path of travel of the teeth on the belt, whereby said teeth are periodically and successively brought into engagement with the toothed wheels to rotate the same and thereby actuate the registers in succession by a step-by-step movement, said teeth varying in length and said toothed wheels varying in position to produce different rates of actuation of said registers, and a summation-

- register for automatically totalizing the actuations of said registers.
31. The combination of a wage-register, an actuating mechanism therefor, means for periodically operating said mechanism to actuate the register, a job register, a motion-transmitting member connected therewith, a shaft driven by said actuating mechanism, a clutch member slidably mounted on said shaft but arranged to rotate therewith, readily adjustable means for sliding said clutch member into engagement with said motion-transmitting member to cause actuation of said job-register concurrently with said wage-register.
32. The combination of a wage-register, a shaft, a register-actuating mechanism secured to said shaft and adapted to rotate the same in a positive direction, a plurality of job-registers, a motion-transmitting member connected with each of said job-registers, a clutch member slidably mounted on said shaft but arranged to rotate therewith, a workman's plug connected with said clutch member and adjustable for sliding the latter into engagement with the motion-transmitting member of any one of said job-registers to cause actuation of the connected job-register concurrently with said wage-register, means on said shaft coöperating with said plug when the latter is in its "out" or inoperative position to prevent connection between the wage-register and its actuating mechanism, means for automatically establishing operative connection between the wage-register and its actuating mechanism when the plug is withdrawn from its "out" position, and means for periodically operating said mechanism to actuate the wage-register and its connected job-register by a step-by-step movement.
33. The combination of a wage-register, a shaft, a register-actuating mechanism secured to said shaft and adapted to rotate the same in a positive direction, a plurality of job-registers, a motion-transmitting member connected with each of said job-registers, a clutch member slidably mounted on said shaft but arranged to rotate therewith, a workman's plug connected with said clutch member and adjustable for sliding the latter into engagement with the motion-transmitting member of any one of said job-registers to cause actuation of the connected job-register concurrently with said wage-register, means on said shaft coöperating with said plug when the latter is in its "out" or inoperative position to prevent connection between the wage-register and its actuating mechanism, means for automatically establishing operative connection between the wage-register and its actuating mechanism when the plug is withdrawn from its "out" position, and means for periodically operating said mechanism to actuate the wage-register and its connected job-register by a step-by-step movement.
34. The combination of a wage-register, a shaft, a register-actuating mechanism secured to said shaft and adapted to rotate the same in a positive direction, a plurality of job-registers, a motion-transmitting member connected with each of said job-registers, a clutch member slidably mounted on said shaft but arranged to rotate therewith, a workman's plug connected with said clutch member and adjustable for sliding the latter into engagement with the motion-transmitting member of any one of said job-registers to cause actuation of the connected job-register concurrently with said wage-register, means on said shaft coöperating with said plug when the latter is in its "out" or inoperative position to prevent connection between the wage-register and its actuating mechanism, means for automatically establishing operative connection between the wage-register and its actuating mechanism when the plug is withdrawn from its "out" position, a time-controlled driving belt having a series of teeth, and a toothed wheel carried by said register-actuating mechanism and projecting into the path of travel of the teeth on the belt, whereby said teeth are periodically brought into engagement with said toothed wheel to rotate the same and thereby concurrently actuate the wage-register and its connected job-register by a step-by-step movement.
35. The combination of a plurality of wage-registers, a corresponding plurality of shafts, actuating mechanism for each register secured to the associated shaft and adapted to rotate the same in a positive direction, a plurality of job-registers, a motion-transmitting member connected with each of said job-registers, a clutch member slidably mounted on each of said shafts but arranged to rotate therewith, a workman's plug connected with each clutch member and adjustable for sliding the same into engagement with the motion-transmitting member of any one of said job-registers to cause concurrent actuation of any wage-register and its connected job-register, means on each of said shafts coöperating with the associated plug when the latter is in its "out" position to prevent connection between the corresponding wage-register and its actuating mechanism, means for establishing operative connection between any wage-register and its actuating mechanism when the corresponding plug is withdrawn from its "out" position, and means for periodically and successively operating the register-actuating mechanisms, whereby the wage-registers are actuated in succession by a time-controlled driving belt having teeth which periodically engage said mechanism to cause operation thereof, whereby the wage-register and its connected job-register are concurrently actuated by a step-by-step movement.

a step-by-step movement, the job-registers being actuated concurrently with the connected wage-registers.

36. The combination of a plurality of wage-registers, a corresponding plurality of shafts, actuating mechanism for each register secured to the associated shaft and adapted to rotate the same in a positive direction, a plurality of job-registers, a motion-transmitting member connected with each of said job-registers, a clutch member slidably mounted on each of said shafts but arranged to rotate therewith, a workman's plug connected with each clutch member and adjustable for sliding the same into engagement with the motion-transmitting member of any one of said job-registers to cause concurrent actuation of any wage-register and its connected job-register, means 15 on each of said shafts cooperating with the associated plug when the latter is in its "out" position to prevent connection between the corresponding wage-register and its actuating mechanism, means for establishing operative connection between any 20 wage-register and its actuating mechanism when the corresponding plug is withdrawn from its "out" position, and a time-controlled driving belt having a series of teeth 25 so arranged that they successively engage said actuating mechanisms to cause operation thereof, whereby the wage-registers are actuated in succession by a step-by-step movement, the job-registers being actuated 30 concurrently with the connected wage-registers.

37. The combination of a plurality of wage-registers, a corresponding plurality of shafts, actuating mechanism for each register secured to the associated shaft and adapted to rotate the same in a positive direction, a plurality of job-registers, a motion-transmitting member connected with each of said job-registers, a clutch member slidably mounted on each of said shafts but arranged to rotate therewith, a workman's plug connected with each clutch member and adjustable for sliding the same into engagement with the motion-transmitting member of any one of said job-registers to cause concurrent actuation of any wage-register and its connected job-register, means on each of said shafts co-operating with the associated plug when the latter is in its "out" position to prevent connection between the corresponding wage-register and its actuating mechanism, means for establishing operative connection between any wage-register and its actuating mechanism when the corresponding plug is withdrawn from its "out" position, a time-controlled driving belt having a series of teeth, and a toothed wheel carried by each of said register-actuating mechanisms and projecting into the path of travel of the teeth on the belt, the said teeth

being so arranged that they are successively brought into engagement with the toothed wheels to rotate the same and thereby actuate the wage-registers in succession by a step-by-step movement, the job-registers being actuated concurrently with the connecting wage-registers.

38. The combination of a plurality of wage-registers, a corresponding plurality of shafts, actuating mechanism for each register secured to the associated shaft and adapted to rotate the same in a positive direction a plurality of job-registers, a motion-transmitting member connected with each of said job-registers, a clutch member slidably mounted on each of said shafts but arranged to rotate therewith, a workman's plug connected with each clutch member and adjustable for sliding the same into engagement with the motion-transmitting member of any one of said job-registers to cause concurrent actuation of any wage register and its connected job-register, means on each of said shafts coöperating with the associated plug when the latter is in its "out" position to prevent connection between the corresponding wage-register and its actuating mechanism, means for establishing operative connection between any wage-register and its actuating mechanism when the corresponding plug is withdrawn from its "out" position, means for periodically and successively operating the register-actuating mechanisms, whereby the wage-registers are actuated in succession by a step-by-step movement, the job-registers being actuated concurrently with the connected wage-registers, and means for varying the rates of actuation of any one or more of said wage-registers.

39. The combination of a plurality of 105
wage-registers, a corresponding plurality of
shafts, actuating mechanism for each register
secured to the associated shaft and adapted
to rotate the same in a positive direction,
a plurality of job-registers, a motion-trans- 110
mitting member connected with each of said
job-registers, a clutch member slidably
mounted on each of said shafts but arranged
to rotate therewith, a workman's plug con-
nected with each clutch member and adjust- 115
able for sliding the same into engagement
with the motion-transmitting member of
any one of said job registers to cause con-
current actuation of any wage-register and 120
its connected job-register, means on each of
said shafts coöperating with the associated
plug when the latter is in its "out" position
to prevent connection between the corre-
sponding wage-register and its actuating 125
mechanism, means for establishing operative
connection between any wage-register and 130
its actuating mechanism when the corre-
sponding plug is withdrawn from its "out"
position, means for periodically and suc-
cessively operating the register-actuating 135

- mechanisms, whereby the wage-registers are actuated in succession by a step-by-step movement, the job-registers being actuated concurrently with the connected wage-registers, and a summation-register for automatically totalizing the actuations of the connected job-registers. 5 "out" position, and a time-controlled driving belt having a series of teeth so arranged that they successively engage said actuating mechanisms to cause operation thereof, whereby the wage-registers are actuated in succession by a step-by-step movement, the job-registers being actuated concurrently with the connected wage-registers, said teeth varying in length to produce different rates of actuation of said wage-registers. 70
40. The combination of a plurality of wage-registers, a corresponding plurality of shafts, actuating mechanism for each register secured to the associated shaft and adapted to rotate the same in a positive direction, a plurality of job-registers, a motion-transmitting member connected with each of said job-registers, a clutch member slidably mounted on each of said shafts but arranged to rotate therewith, a workman's plug connected with each clutch member and adjustable for sliding the same into engagement 75 with the motion-transmitting member of any one of said job-registers to cause concurrent actuation of any wage-register and its connected job-register, means on each of said shafts coöperating with the associated plug 80 20 when the motion-transmitting member of any one of said job-registers to cause concurrent actuation of any wage-register and its connected job-register, means on each of said shafts coöperating with the associated plug 85 25 when the latter is in its "out" position to prevent connection between the corresponding wage-register and its actuating mechanism, means for establishing operative connection between any wage-register and its 90 30 actuating mechanism when the corresponding plug is withdrawn from its "out" position, means for periodically and successively operating the register-actuating mechanisms, whereby the wage-registers are actuated in 95 35 succession by a step-by-step movement, the job-registers being actuated concurrently with the connected wage-registers, means for varying the rates of actuation of any one or more of said wage-registers, and a summation-register for automatically totalizing the 100 40 actuations of the connected job-registers. 105
41. The combination of a plurality of wage-registers, a corresponding plurality of shafts, actuating mechanism for each register secured to the associated shaft and adapted to rotate the same in a positive direction, a plurality of job-registers, a motion-transmitting member connected with each of said job-registers, a clutch member slidably 110 45 mounted on each of said shafts but arranged to rotate therewith, a workman's plug connected with each clutch member and adjustable for sliding the same into engagement with the motion-transmitting member of any one of said job-registers to cause concurrent actuation of any wage-register and its connected job-register, means on each of said shafts coöperating with the associated plug 115 50 when the latter is in its "out" position to prevent connection between the corresponding wage-register and its actuating mechanism, means for establishing operative connection between any wage-register and its actuating mechanism when the corresponding plug is withdrawn from its "out" position, a time-controlled driving belt having a series of teeth, and a toothed wheel carried by each of said register-actuating mechanisms and projecting into the path of travel of the teeth on the belt, the said teeth being so arranged that they are successively brought into engagement with the toothed wheels to rotate the same and thereby actuate the wage-registers in succession by a step-by-step movement, the job-registers being actuated concurrently with the connected wage-registers, said teeth varying in length and said toothed wheels varying in position to produce different rates of actuation of said wage-registers. 120
43. The combination of a plurality of wage-registers, a corresponding plurality of shafts, actuating mechanism for each register secured to the associated shaft and adapted to rotate the same in a positive direction, a plurality of job-registers, a motion-transmitting member connected with each of said job-registers, a clutch member slidably mounted on each of said shafts but arranged to rotate therewith, a workman's plug connected with each clutch member and adjustable for sliding the same into engagement with the motion-transmitting member of any one of said wage-registers and its connected job-register, means on each of said shafts coöperating with the associated plug 125 55 when the latter is in its "out" position to prevent con- 130

- nection between the corresponding wage-
register and its actuating mechanism, means
for establishing operative connection be-
tween any wage-register and its actuating
mechanism when the corresponding plug is
5 withdrawn from its "out" position, a time-
controlled driving belt having a series of
teeth, a toothed wheel carried by each of
said register-actuating mechanisms and pro-
jecting into the path of travel of the teeth
10 on the belt, the said teeth being so arranged
that they are successively brought into en-
gagement with the toothed wheels to rotate
the same and thereby actuate the wage-reg-
isters in succession by a step-by-step move-
15 ment, the job-registers being actuated con-
currently with the connected wage-registers,
said teeth varying in length and said toothed
wheels varying in position to produce differ-
20 ent rates of actuation of said wage-registers,
and a summation-register for automatically
totalizing the actuations of the connected
job-registers. 44. In combination, a wage-register, actuating
25 mechanism therefor, a shaft adapted to be driven by said mechanism, a job-register, a workman's plug provided with means for connecting said shaft and job-register together when the plug is moved to "in" position, said plug being adapted when moved to "out" position to automatically disconnect said actuating mechanism from the register, and means for periodically actuating the wage-register and its connected
30 job-register by a step-by-step movement. 45. In combination, a plurality of registers, actuating mechanism associated with each register, a common driving device for all of said registers, and cooperating means
35 carried by said device and each of said actuating mechanisms for periodically and successively establishing mechanical connection between said driving device and said mechanisms, whereby the registers are actuated in
40 succession by a step-by-step movement. 46. In combination, a plurality of registers provided each with an actuating mechanism, and a common time-controlled driving device for all of said registers adapted to
45 successively engage said mechanisms at different predetermined intervals, whereby said registers are actuated in succession by a step-by-step movement at different rates of actuation. 55 47. In combination, a plurality of registers provided each with an actuating mechanism, a common time-controlled driving device for all of said registers adapted to successively engage said mechanisms at different predetermined intervals, whereby said registers are actuated in succession by a step-by-step movement at different rates of actuation, and a summation register for automatically totalizing the actuations of said
60 registers. 48. In combination, a plurality of wage-registers, a plurality of job-registers, means for selectively establishing mechanical connection between any wage-register and any job-register, and a common time-controlled driving mechanism adapted to become momentarily geared to said wage-registers in succession at varying periodic intervals, whereby said wage-registers are actuated successively by a step-by-step movement at different rates of actuation, the job-registers being actuated concurrently with the connected wage-registers. 49. In combination, a plurality of wage-registers, a plurality of job-registers, means for selectively establishing mechanical connection between any wage-register and any job-register, a common time-controlled driving mechanism adapted to become momentarily geared to said wage-registers in succession at varying periodic intervals, whereby said wage-registers are actuated successively by a step-by-step movement at different rates of actuation, the job-registers being actuated concurrently with the connected wage-registers, and a summation register for automatically totalizing the actuations of the connected job-registers. 50. The combination with a register, of a time-controlled driving mechanism therefor adapted to be momentarily geared to said register at periodic intervals to actuate said register by a step-by-step movement. 51. The combination with a plurality of registers, of a time-controlled driving mechanism adapted to become momentarily geared to said registers in succession at varying periodic intervals, whereby the registers are successively actuated at predetermined rates of actuation by a step-by-step movement. 52. The combination with a plurality of registers, of a time-controlled driving mechanism adapted to become momentarily geared to said registers in succession at varying periodic intervals, whereby the registers are successively actuated at predetermined rates of actuation by a step-by-step movement, and means for automatically totalizing the actuations of said registers. 53. The combination with a register, of a continuously operating driving mechanism adapted to make momentary mechanical connection with said register at periodic intervals to actuate said register by a step-by-step movement. 54. The combination with a plurality of registers, of a continuously operating driving mechanism adapted to make momentary mechanical connection with said registers in succession at periodic intervals, whereby the registers are successively actuated by a step-by-step movement. 55. The combination of a wage-register, a job-register, continuously operating time

controlled mechanism for actuating said registers by a step-by-step movement, and means for establishing mechanical connection between said mechanism and said registers by a single operation.

56. The combination of a wage-register, a plurality of job-registers, continuously operating time-controlled mechanism for actuating the registers by a step-by-step movement, and an adjustable connecting device for mechanically connecting said wage-register and any desired job-register with said mechanism by a single operation.

57. The combination of a plurality of registers, continuously operating time-controlled mechanism for actuating the con-

nected registers by a step-by-step movement, and means for establishing mechanical connection between said mechanism and any desired register.

20

58. In combination, a register, a uniformly moving operating mechanism having actuating devices of different rates, and means for mechanically connecting the register with a desired one of such devices.

25

In witness whereof, I hereunto subscribe my name this 20th day of February A. D. 1909.

WILLIAM J. CRUMPTON.
